4 Claims. (Cl. 123—73)

1

This invention relates to improvements in internal combustion engines, and more particularly to improved supercharging and cylinder fuel intake provisions for two-cycle engines of crankcase charged, uni-flow scavenging type.

An object of the present invention resides in the provision in a two-cycle, crankcase charged engine, of a centrifugal type supercharger having the major portion thereof integral with the engine crankshaft, and effective for increasing the volume and pressure of the fuel charge in the crankcase, whereby to improve the power and operating efficiency of the engine.

Another object is to provide in an engine of the character indicated, a centrifugal supercharger of shrouded impeller construction, which is operable to effect in a positive manner, introduction of fuel mixture under pressure into the engine crankcase and in so doing, to cause break-up or atomization of liquid fuel particles, for effecting an intimate mixture of the fuel and air in the crankcase.

Other objects and advantages of the present invention will appear from the following description of a presently preferred embodiment thereof, as illustrated in the accompanying drawing, wherein:

Fig. 1 is a longitudinal sectional elevation through an engine crankcase and cylinder assembly, illustrating features of the invention including a supercharger on the crankshaft;

Fig. 2 is a sectional view as taken along the line 2—2 in Fig. 1, showing the manner of fuel charge admission to a ported passage in the crankshaft and,

Fig. 3 is an enlarged fragmentary sectional view of the crankshaft in the portion thereof embodying the presently improved centrifugal type supercharger.

Referring to the drawing by suitable characters of reference, Fig. 1 illustrates a two-cycle, crankcase charged internal combustion engine comprising a cylinder 10 mounted on a crankcase 11, a piston 12 reciprocable in the cylinder and operatively associated with the crankshaft 14 through a connecting rod 15. The crankcase comprises an end wall 16 in which the end portion 18 of the crankshaft is journaled, as by the bearing 19, an opposite end wall structure 20 of a character presently to be described, and a wall member 22 shown at the bottom of the crankcase, which wall is extended upwardly on either side (not shown) to form the crankcase side walls. A removable drain plug 23 is located as shown, in the wall 22. The

2

crankcase wall 20 has a hub extension 24 in which the crankshaft end portion 26 is journaled, as by a sleeve bearing 27, a suitable seal 28 being provided between the outer end of the hub 24 and the crankshaft. The crankshaft extends beyond hub 24 and supports a pulley 30 for driving connection through a V-belt 31, with the pulley 32 of a cooling fan 34 rotatably mounted in engine frame part 35.

10 The cylinder 10 is provided with an exhaust port 36 in its head end, which is controlled by exhaust valve 38, the latter being engine operated and timed in conventional manner (not shown). In the lower section of the cylinder are a plurality of fuel charge admission passages 39 (Fig. 1) formed in the inner surface of the cylinder, the lower ends 40 of the passages being at all times open directly to the crankcase chamber 42. As appears in Fig. 1, the admission passages are piston controlled.

15 The crankshaft 14 is provided as a one-piece casting, to include a crank cheek 43, crank pin 44, and opposite crank cheek 46 from which projects the crankshaft portion 26. In constructing the crankshaft, the circular crank cheek or disc 46 is formed to provide as an integral structure, an imperforate disc wall 47, a centrifugal hub 48 adjoining the shaft portion 26, and a plurality of equally spaced, radial vanes 50 extending from the hub 48 to the periphery 51 of the cheek disc 47. Each vane is of generally triangular form as clearly appears in Figs. 1 and 3. The vanes form passages 52 on one side by the disc 47. The open sides of these passages are closed 20 by the portion 54 of crankcase end wall 23, which presents a frusto-conical surface 55 positioned to have a minimum clearance with the margins 56 of the vanes (Fig. 1). The crankshaft is cored to provide a passage 60 in the portion 26 thereof, the passage extending to a port 61 opening laterally of the crankshaft section. At its other end, the passage is continued through branch passages 62 opening through ports 64 to each of the vane passages 52.

25 From the foregoing, it will appear now that the vane structure described constitutes a positive displacement, centrifugal blower or supercharger of shrouded impeller form, provided in major portion, as an integral part of the crankshaft.

30 Referring to Fig. 2, suitably supported on the engine is a carburetor generally indicated at 65, which may be of any well-known or prevailing type. The carburetor delivers carbureted fuel charge to a passage 66 provided in a lateral ex-

tension 67 of the crankcase hub 24, the passage communicating with an enlarged port 68 provided in the sleeve bearing 27. Sleeve bearing port 68 is located so that the crank shaft passage port 61 will register therewith once in each revolution of the crankshaft, whereby to admit fuel charge to the crankshaft passage 60 for flow to the supercharger.

In operation, in the suction cycle of the engine, fuel charge will be drawn from the carburetor principally in consequence of supercharger operation, passing through the passage 66, port 68, crankshaft port 61 open to the latter, and thence through crankshaft passage 60 and ports 64 to the supercharger. The supercharger discharges the fuel charge under pressure, into the crankcase chamber 42. Upon piston opening of the cylinder admission passages 39, the pressured fuel will flow into the cylinder to charge the same and at the same time, to complete cylinder scavenging through the open exhaust port. On upward movement of the piston, the charge is compressed and then ignited by spark plug 70, followed by the power stroke of the piston.

It will appear now that the supercharger affords positive charging of the crankcase with fuel under pressure therein and filling the cylinder admission passages 39, so that the pressured fuel is available for quick admission to the cylinder as the piston uncovers the passages 39. Nearly or substantially complete cylinder scavenging of gases and products of combustion, is facilitated herein by the above-atmospheric pressure of the fuel charge entering the cylinder. Moreover, the positive displacement supercharger which charges the crankcase with fuel under a pressure above atmospheric pressure, serves advantageously to break-up liquid fuel particles and cause intimate mixture of the fuel and air, thereby improving the character of the fuel supply in the crankcase. The foregoing features afford marked improvement in the power and operating efficiency of the engine.

Having described the invention with respect to a presently preferred embodiment thereof, what I desire to claim and secure by Letters Patent is:

1. In an internal combustion engine, a crankcase, a crankshaft rotatable therein, means for introducing fuel mixture into the crankcase, including a blower having an impeller formed integral with the crankshaft, wherein the impeller includes a circular wall and vanes thereon tapering convergently toward the periphery of said wall and forming passages, the wall closing one side of the passages, and said crankcase having a wall portion in close proximity to the impeller, closing the other side of said passages.

2. In an internal combustion engine of crank-

case charged type, a crankcase, a crankshaft rotatable therein, said crankshaft having a fuel mixture passage, and a supercharger for charging the crankcase with fuel mixture under above-atmospheric pressure, wherein the supercharger comprises an impeller formed integral with the crankshaft, providing substantially radial passages and a circular wall closing one side of the passages, a wall element on said crankcase in close proximity to the impeller, closing the other side of said passages, and said crankshaft providing openings communicating said radial passages with said crankshaft passage.

3. In an internal combustion engine of crankcase charged type, a crankcase, a crankshaft rotatable therein, and a supercharger for charging the crankcase with fuel mixture under above-atmospheric pressure, wherein said supercharger comprises a circular wall element integral with the crankshaft, radial vanes on said wall element defining passages therebetween, closed on one side by the wall element, said vanes being tapered toward the periphery of the wall element, and said crankcase having a wall portion presenting a frusto-conical face closely adjacent the vanes and closing said passages.

4. In an internal combustion engine of crankcase charged type, a crankcase, a crankshaft rotatable therein, and means for charging the crankcase with fuel mixture, comprising a carburetor having an outlet duct terminating in a port, said crankshaft having a duct therein terminating in a port in one side of the crankshaft such as to be registerable with said port of the carburetor outlet duct, a supercharger impeller integral with the crankshaft, providing substantially radial passages and a wall closing one side of the passages, said crankcase having a wall portion in close proximity to the impeller and closing the other side of said passages, and said crankshaft having passage means separately communicating each of the impeller passages with said crankshaft duct.
